REFRIGERATION

Gustav Mårten Blomqvist and Sture Folke
Torstensson, Stockholm, Sweden, assignors, by
mesne assignments, to Servel, Inc., New York,
N. Y., a corporation of Delaware

Application January 13, 1938, Serial No. 184,760

3 Claims. (Cl. 62—1)

This invention relates to refrigeration, and it is an object to provide an improved tool to facilitate the removal of ice or other frozen matter from a shallow tray adapted for use in household refrigerators.

The above and other objects and advantages of the invention will be better understood from the following description taken in conjunction with the accompanying drawing forming a part of this specification, and of which:

10 Fig. 1 illustrates a tool embodying the invention which is disposed about a shallow ice tray partly withdrawn from a freezing compartment of a cooling element;

Fig. 2 is a view taken on line 2—2 of Fig. 1 to illustrate more clearly the relative positions of the cooling element, tray, and tool; and

Fig. 3 is a side elevation of a tray partly withdrawn from a cooling element and having the tool in a different position about the tray.

20 Referring to Figs. 1 and 2, an evaporator or cooling element 10 of a household refrigerator is refrigerated in any suitable manner. The cooling element 10 is provided with a plurality of ice freezing compartments 11 which are adapted to receive shallow ice trays 12 having a resilient bottom and side walls.

25 The tray 12 may be formed of suitable metal, such as aluminum or stainless steel, for example, and about the upper edges of the side walls is provided an outwardly extending flange 14. The flange at one end wall may extend downward, as indicated at 15, to provide a finger grip for the tray. Within the ice tray 12 is positioned 30 a removable grid member 16 which may have a longitudinal dividing wall and spaced transverse dividing walls to form ice cube compartments.

35 In accordance with the invention a tool 17 is provided to facilitate the removal of ice or other frozen matter from tray 12. The tool 17 comprises a handle portion 18 and forked parallel arms 19 and 20 which are spaced apart a distance slightly greater than the depth of the tray. The outer end 21 of handle 18 is preferably tapered or pointed. Referring to Fig. 2, it will be seen that when the arm 19 is directly above the arm 20 the handle portion 18 is in the same vertical plane as the arms 19 and 20.

40 In using the tool just described, the tray 12 is filled with water or other matter to be frozen and inserted in the freezing compartment or support 11. With tray 12 positioned on shelf 22, heat is removed through the bottom of the tray, due to the production of cold by the cooling

element, whereby ice is formed in the tray. To remove tray 12 from the freezing compartment 11, the tapered end 21 of the tool 17 may be inserted between the tray bottom and shelf 22 to break the ice bond that may be formed between the tray bottom and shelf.

The tray 12 is partly withdrawn from the freezing compartment 11 and the tool positioned transversely of the tray with the arm 19 disposed above the top of the tray and arm 20 disposed across the bottom of the tray. The handle 18 is then pressed downward whereby the tray is first tilted slightly until the flange 14 of one longitudinal side wall bears against the top horizontal wall 23 of the freezing compartment and the bottom edge of the opposite longitudinal side wall bears against the bottom horizontal wall or shelf 22. With continued downward pressing on handle 18 after the rear portion of the tray becomes wedged or locked in the freezing compartment, sufficient deformation of the tray is brought about to break the ice bond and loosen the ice cubes or frozen matter from the tray.

Instead of positioning the tool 17 transversely of the withdrawn portion of the tray 12, the tool 17 may be positioned longitudinally of the withdrawn front part of the tray with the arms 19 and 20 extending rearwardly from the front end wall of the tray. When the handle 20 is pressed downward the tray is tilted slightly until the flange 14 of the rear end wall bears against the top horizontal wall 23 and an intermediate portion of the tray bottom bears against the forward edge of shelf 22. With the tray 12 wedged or locked in position in the freezing compartment or support 11, continued downward pressing on handle 18 causes sufficient deformation of the tray to loosen the ice cubes or frozen matter from the tray.

In order to resist corrosion, the tool 17 may be formed of stainless steel or steel which is chromium-plated. If desired, the arms 19 and 20 may be covered with rubber tubing to protect the portions of the tray against which they bear when the tool is being used to facilitate the loosening of frozen matter.

Although a particular embodiment of the invention has been shown and described, it will be apparent that various modifications and changes may be made without departing from the spirit and scope of the invention, as pointed out in the following claims.

What is claimed is:

1. The combination with a shallow ice tray

- for use with household refrigerators and adapted to contain matter to be frozen in a freezing unit, said tray being formed of sheet metal, of an independent device including a part having
- 5 a tapered end portion which may be inserted between the tray bottom and shelf of the freezing unit upon which it rests to break the ice bond which may be formed therebetween, and said device having additional parts adapted to
- 10 grip different regions of said tray whereby said tray can be distorted by said first-mentioned part to break the bond of the frozen matter and facilitate the removal of the frozen matter from said tray.
- 15 2. The combination with a shallow tray for use with household refrigerators and adapted to contain matter to be frozen therein, and a support in which a part of said tray may be positioned, of a device including a handle and
- 20 members adapted to be positioned about and embrace another part of said tray, and said device being constructed and arranged so that with movement thereof by said handle said members are capable of exerting force on said tray while it is wedged and locked in said support to cause sufficient deformation of said tray to break the bond with the frozen matter and facilitate the removal of the frozen matter from said tray, said handle having a tapered end por-

tion which may be inserted between the tray bottom and support upon which it rests to break the ice bond which may be formed therebetween.

3. The combination with a shallow ice tray for use with household refrigerators and adapted to contain matter to be frozen in a compartment of a freezing unit, said tray being formed of sheet metal, of an independent device including a handle and a pair of arms spaced apart substantially the same distance as the depth of said tray, and said arms being adapted to embrace a forward part of said tray while said tray is partly withdrawn from said compartment, and said device when turned by said handle being capable of wedging said tray in said compartment and distorting said tray to break the ice bond with the frozen matter and facilitate the removal of the frozen matter from said tray, said handle being substantially in the same vertical plane as said arms when one arm is directly above the other, and said handle having a tapered end portion which may be inserted between the tray bottom and shelf of the freezing unit upon which it rests to break the ice bond which may be formed therebetween.
